Geo. C. Scher

INVENTOR
BY Louis Scher
REPRESENTATIVE AND ATTORNEY.

UNITED STATES PATENT OFFICE.

LOUIS SCHER, OF NEW YORK, N. Y., ASSIGNOR, BY MESNE ASSIGNMENTS, TO DICTOGRAPH PRODUCTS CORPORATION, A CORPORATION OF VIRGINIA.

DICTOGRAPH.

1,317,991.

Specification of Letters Patent. Patented Oct. 7, 1919.

Application filed February 26, 1918. Serial No. 219,215.

To all whom it may concern:

Be it known that I, LOUIS SCHER, a citizen of the United States, residing at the city of New York, in the borough of Bronx 5 and State of New York, have invented certain new and useful Improvements in Dictographs, of which the following is a full, clear, and exact description.

This invention relates to the "dictograph" 10 or detective telephone, the primary object being to provide means whereby the transmitter of an ordinary service telephone may be used as the transmitter of a dictograph circuit without apparent evidence that the 15 service telephone has been adapted for such use.

The ordinary dictograph or detective telephone comprises a simple circuit containing a battery, a transmitter and a receiver, the transmitter being usually located in a room or apartment where conversation is to be carried on which it is desired to hear, the instrument being hidden or placed in some inconspicuous place where its presence 25 will not be detected by the persons subjected to the espionage. The receiver is placed in any other convenient locality where the transmitted conversation may be heard without the knowledge of the persons speaking.

The dictograph has become of such universal use that dishonest persons and sometimes others who do not wish their conversation to be overheard often make a search 35 for a hidden transmitter before they indulge in conversation, and since these conversations very often, if not usually, occur in business offices where an ordinary service telephone is installed, it is apparent that if 40 such telephone could be used as a part of the dictograph system without so altering the service telephone as to give rise to the suspicion that it was being used for dictograph purposes, it would constitute a valuable addition to the dictograph art.

My invention therefore consists broadly in combining the dictograph circuit with the service telephone circuit in such a manner that the combination cannot be detected by 45 ordinary observers. The manner of accomplishing this will be described in connection with the accompanying drawing, in which the figure is a diagram of the circuits and instruments comprised in a service telephone

substation and a dictograph receiving station connected for co-operation, as contemplated by my invention.

The ordinary service telephone substation now commonly used comprises a stationary call-box to which the two wires of the external circuit lead and which contains the ordinary signal operated from the central office to summon the subscriber, and a portable telephone set comprising a transmitter, a receiver and a hook switch or its equivalent, which are mounted upon a stand in a manner to be conveniently held in the hand when in use, this stand being connected with the stationary call-box by means of a single cable carrying the various conductors required for the service.

In the drawing, 1 indicates the call-box to which the two external wires 2 and 3 lead and are permanently connected at binding posts 4 and 5, respectively. The bell is 75 conventionally represented at 6 and is operated in the usual manner, it having nothing to do with the present invention. The portable telephone set, which is understood to be mounted upon a portable stand convenient to be handled, but which is not shown, consists of the transmitter T, the receiver R and the hook switch S. Three conductors ordinarily extend from the call-box to the portable set. These are represented 80 by 7, 8 and 9, respectively, being attached to binding posts 10, 11 and 12 in the box, the conductor 7 leading to one side of the transmitter and thence by wire 13 to the switch lever, the conductor 8 leading to one side 85 of the receiver, and thence by wire 14 to one of the contacts 15 of the switch, and the wire 9 leading to a second switch contact 16. With the receiver R on the hook, the circuits of the two instruments are open, as usual, 90 the only closed circuit being from the central office through the signal in the box. The three conductors 7, 8 and 9 are usually combined into a single flexible cable having 95 the familiar green silk insulation or covering. In order to convert this telephone substation for dictograph purposes it is only necessary to add one conductor to the cable connecting the box with the portable set and I contemplate doing this by removing the 100 original three-conductor cable entirely and substituting a four-conductor cable, which will also be provided with the green silk

insulation so that it will have the same external appearance as the original cable and will differ therefrom only in that it will be slightly larger in diameter, a fact which 5 would not be discovered by the ordinary observer. In substituting this four-conductor-cable for the original cable, three of the wires will be connected respectively with the box and the instruments, exactly as the 10 three wires 7, 8 and 9 are connected, while the fourth wire indicated by 17, will be permanently connected in the portable set with the wire 13 at some point between the transmitter and the switch lever, while in the box 15 its end will remain loose for connection with one of the wires of the dictograph circuit. At the receiving end of the dictograph circuit there is located a telephone receiver R', a battery B and a rheostat r. These devices 20 will ordinarily be contained in a portable box (not shown) having two binding posts 18 and 19 between which the several devices are connected in series. The devices are then connected with the service telephone 25 by running one conductor 20 from post 18 to post 4 of the call-box, with which the main conductor 2 is connected. Another wire 21 is run to the call-box and connected with the loose end of the wire 17 therein. 30 Conductor 20 connects with conductor 7 by way of the permanent connection 22 between the posts 4 and 10. It will thus be seen that the two wires 20 and 21 are permanently connected to the respective terminals of the 35 transmitter T of the service telephone and that this connection is not affected in any manner by the operation of the hook switch. The receiver R' of the dictograph is a supersensitive instrument capable of responding to and reproducing any sounds 40 delivered to the transmitter T even though the source of the sound is somewhat distant from the transmitter. Persons entering a room for the purpose of a conference will 45 ordinarily take seats at a desk or table adjacent to which the service telephone is installed, and will thus be located at only short distances from the transmitter. To such persons the converted telephone will give 50 no indication of its conversion, and while the telephone remains on the hook it will be supposed by such persons that the telephone is inoperative to convey their conversation. As a matter of fact, however, it will be seen 55 that notwithstanding that the receiver is on the hook any sounds delivered to the transmitter will be conveyed to the receiver R' by the battery B, over the following circuit: from transmitter T, by wire 7, wire 22, wire 60 20, post 18, rheostat r, battery B, receiver

R', post 19, wire 21, wire 17 and wire 13, to transmitter.

The function of the rheostat r at the receiving end is to enable the listener to adjust the resistance of the circuit for the best 65 effect upon the receiver R'. The length of the wires 20 and 21 will vary with different installations and the rheostat is used to compensate for these variations.

The term "hook switch" is used herein to 70 cover any switch that normally holds the circuit of the transmitter and receiver of the substation open, but which closes those circuits while conversation is carried on; hence whether such switch be gravity or 75 manually operated is immaterial.

I claim:

1. A subscriber's telephone station including a switch controlling the normal circuits of the station transmitter and receiver, 80 in combination with another receiver and a circuit including the same and the station transmitter and excluding the switch.

2. A subscriber's telephone station including a switch controlling the normal circuits of the station transmitter and receiver, 85 in combination with a circuit including another receiver, a battery and the station transmitter and excluding the switch.

3. A telephone substation comprising a 90 portable transmitter and receiver set, a hook switch and a signal box connected therewith by a single multiple conductor cable, two of the conductors of said cable extending to the respective terminals of the transmitter in- 95 dependent of the hook switch and affording a permanently closed portion of a circuit including the transmitter.

4. A telephone substation comprising a 100 portable transmitter, receiver and hook switch, a stationary call-box and a single multiple conductor cable connecting the set with the box, three wires of said cable extending to the transmitter, one of which is normally open at the hook switch while the 105 other two are permanently closed, in combination with a second receiver in circuit with said permanently closed wires.

5. A telephone substation comprising a 110 transmitter, receiver and switch, a call box and a plurality of conductors connecting the set with the box, three of said conductors extending to the transmitter, one of which is normally open at the switch while the other two are permanently closed, in combination with a second receiver in circuit 115 with said permanently closed wires.

In witness whereof, I subscribe my signature.

LOUIS SCHER.
